UNITED STATES PATENT OFFICE.

JOHN H. VINTON, OF BOSTON, MASSACHUSETTS, ASSIGNOR TO THE TRIMONT MANUFACTURING COMPANY, OF PORTLAND, MAINE.

CHAIN WRENCH.

SPECIFICATION forming part of Letters Patent No. 522,136, dated June 26, 1894.

Application filed December 11, 1893. Serial No. 493,313. (No model.)

To all whom it may concern:

Be it known that I, JOHN H. VINTON, of Boston, county of Suffolk, State of Massachusetts, have invented an Improvement in 5 Chain Wrenches, of which the following description, in connection with the accompanying drawings, is a specification, like letters and figures on the drawings representing like parts.

10 The invention has for its object the production of a durable, strong, simple and efficient chain wrench of great power, and one by which a pipe may be handled without the free end of the chain becoming accidentally 15 loosened from the head of the wrench.

Figure 1 is a view of one side of the head of the wrench with the chain detached. Fig. 2 is a perspective detail showing uppermost the opposite face of the head of the wrench and 20 the chain. Fig. 3 is a plan view of that side of the head of the wrench which is up in Fig. 2, the jaws being partially broken off, the dotted lines representing the chain in position; and Fig. 4 shows in longitudinal section the 25 head of the wrench, with a chain embracing a piece of pipe.

The handle A of the wrench may be of any suitable size as to diameter and length, and of any suitable material. The head of the 30 wrench is composed preferably of a forging B to which is adjustably secured by set screws a, suitable rigid steel jaws B', preferably in the shape of segments with teeth to engage the pipe P. The head of the wrench has at 35 one side of it a suitable pin, as b, in ears b', said pin serving to connect one link, as c, of the chain C, to the head. The opposite side of the head is provided with lips d, d, concaved at their rear sides, as at d', and brought 40 nearly together at their outer ends, as in Fig. 3, the spaces between the lips d being substantially of a thickness of the link of a chain. The concavities d' of the lips are of such shape as to receive the end of one of the links 45 of the chain, and project rearwardly there-over or overhang as represented in dotted lines by the link c², Fig. 3, and by link c³ full lines Fig. 4. The head is also slotted longitudinally, as at d³, from a point back of said 50 lips toward the handle of the wrench, and also forward of said lips, so that the end of

the link c³ joining the link c², as well as the link c⁴, may rest with their edges in said slot, the said slot being extended preferably forward to the outer end of the head, as to the 55 point 4, see Figs. 1 and 4.

As described and represented it will be understood that the chain, when laid about a pipe, as represented in Fig. 4, and drawn up taut, will have one of its links, as for instance, the link c³ laid in between the lips d and the end of the link c² nearest the toothed end of the head will enter the concavities d' of the lips and fit said concavities in such manner that the chain cannot be disengaged 60 from between the lips unless the chain is moved in the direction of the arrow near it in Fig. 4 sufficiently to draw the round end of the link c³ out from said concavities and beyond the rearward overhanging portions of 65 the lips when the link c³ may be lifted from between the inner walls of the lips d. In practice the lips d are so shaped as to receive and fit the links and hold on to the chain and keep the latter seated without any liability 70 of the free end of the chain becoming accidentally detached from the head while the wrench is being used.

The chain shown is an ordinary round link chain, a form of chain inexpensive to construct, and yet of great strength.

Having described my invention, what I claim, and desire to secure by Letters Patent, is—

1. In a chain wrench, a head B having rigid 85 toothed jaws B', and provided with lips b concaved at their sides farthest from the said jaws and shaped to present over-hanging portions, said lips at their concaved sides presenting a flat surface upon which may 90 rest the two sides of a chain link while the over-hanging portions of the lips embrace the end of said link, the slot between the lips d being extended down below the surface upon which rests the flat link and being made 95 to intersect a groove, d³, which shall receive the lower half of a vertically held link to prevent twisting thereof substantially as described, the over-hanging lips and groove positively retaining the chain in place. 100

2. In a chain wrench, a head B having rigid toothed jaws B' and provided with lips con-

caved at their sides farthest from the said jaws, to form overhanging portions said head being longitudinally slotted, as at d^3 , from a point behind said lips to a point in front of 5 said lips toward said jaws, and a chain having a series of links substantially as shown, one of the links of said chain being adapted to stand vertically between said lips, and also to enter said slot d^3 while the next link of the 10 chain enters by its round end the concavities

of the lips and is retained therein by their overhanging portions, substantially as described.

In testimony whereof I have signed my name to this specification in the presence of two subscribing witnesses.

JOHN H. VINTON.
